Primary Examiner — Michelle E. Wilson*Assistant Examiner* — Jessie A Kwasney(74) *Attorney, Agent, or Firm* — Amit Kulkarni(57) **CLAIM**

The ornamental design for a cleaning pig, as shown and described.

DESCRIPTION

FIG. 1 is a front and top perspective view showing our new design;

FIG. 2 is a rear and bottom perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is an exploded view of a front and top perspective view thereof; and,

FIG. 8 is an exploded view of a rear and bottom perspective view thereof.

1 Claim, 8 Drawing Sheets(56)
